BARREL

Bertil T. Lindell, Detroit, Mich., assignor to The Murray Corporation of America, a corporation of Delaware

Application November 6, 1933, Serial No. 696,751

6 Claims. (Cl. 220—10)

My invention relates to barrels and particularly to a barrel of the all-metal type having an inner and outer shell portion which are entirely insulated from each other.

In the copending application of C. H. Widman, A. P. Nacey and B. T. Lindell Serial No. 673,350 filed May 29, 1933, and assigned to the assignee of the present invention, a barrel was disclosed wherein reinforcing and insulating portions were provided for supporting and sealing the inner container portion against a transfer of heat. The present invention is a further extension of the novelty of the above mentioned barrel in that the inner and outer container portions are pre-formed in such manner that when joined together the insulating material is disposed between congruous surfaces which are shaped in such manner as to provide lateral and longitudinal support at the shoulder portions of the barrel. In this manner the barrel is completely insulated except for the metal bungs where some transfer of heat will naturally occur owing to their direct contact with the contained liquid.

The chimes of the barrel are formed about laterally extending rings to provide material width 25 to the ends of the barrel for stacking purposes and as a further assurance against slippage the ends are roughened, preferably by having the manufacturer's name embossed thereon. The barrel is reinforced at the bilge and the metal of 30 the inner and outer container portions at the bung is joined together in a single weld to prevent the possibility of leakage between the inner and outer container portions.

Accordingly, the main objects of my invention 35 are; to construct a barrel of inner and outer metal containers which are entirely insulated from each other; to provide a container portion for a barrel having preformed shoulders which mate with preformed portions of the outer reinforcing elements of the barrel so as to provide complementary surfaces between which a substantially unyielding insulating material may be disposed; to provide substantially rigid insulating material between complementary surfaces of inner and outer container portions of a barrel which 45 are so formed as to provide lateral and longitudinal support for the inner container portion; to provide laterally extended rings in the chime ends to form barrel ends which are flat for stacking purposes; to emboss indicia on the ends of the chimes to prevent slippage when stacked and in general, to construct a barrel of the all-metal, insulated type which is simple in construction, which is rugged and which is economical of manufacture.

Other objects and features of novelty of my invention will be either specifically pointed out or will become apparent when referring, for a better understanding of my invention, to the

following description taken in conjunction with the accompanying drawing, wherein:

Figure 1 is a broken view, partially in section and partly in elevation, of a barrel embodying features of my invention.

Fig. 2 is an enlarged broken sectional view of the structure illustrated in Fig. 1.

Fig. 3 is a view of structure similar to that illustrated in Fig. 2, showing a modified form thereof, and

Fig. 4 is a reduced plan view of the structure illustrated in Fig. 1.

The metal barrel herein illustrated and described somewhat follows the construction illustrated and described in the above mentioned copending application. The inner container portions 10 are of similar construction being stamped from the same dies to have the reversely bent shoulder portions 11 therein by which the inner container portions are supported against lateral or longitudinal movement. One of the container portions 10 has a central hole formed therein, the metal being flanged in Z-shape, as at 12, illustrated in Fig. 1. A collar 13 is mated therewith and flanged over at 14 and preferably brazed or otherwise secured to the marginal edge of the Z-shaped marginal flange 12. A thread 15 is provided on the collar 13 in which a tap-bung 16 is secured. The two portions 10 are mated together at the bilge and are secured in unit construction by a welding operation at 17, as illustrated in Figs. 1, 2 and 3.

Like reinforcing outer portions 18 are of pot shape having pressed-in end portions 19 which are further preformed at 21 to form a deep chime groove and a reversely curved surface 22 which is similar in shape to the curved surface 11, the purpose of which will be explained more fully hereinafter. A semi-circular bung opening 23 is provided in each one of the container portions 10 and the reinforcing portions 18. A central opening 24 is provided in the end 18 of one of the portions 18 having an outward flange 25 on the edge thereof which mates with the flange 26 provided on the edge of the Z-shaped flange 12 of the inner container portion 10. Before assembly a reinforcing belt 27 is secured to one of the reinforcing portions preferably by welding at 28 and a bung 29 is brazed or otherwise secured to the outwardly directed flange 31 at the margin of the semi-circular openings 23 in each one of the liquid containing portions 10.

An annular insulating ring 32 is placed over the surface 22 as illustrated in Fig. 1 and the inner container portions 10 after being secured together are set within the lower reinforcing portion 18. An upper insulating ring is then placed on the top of the container portion 10 and the upper reinforcing portion 18 is disposed over the belt 28 and is forced down into a position to abut

against the edge of the bottom reinforcing portion 18. The two portions are then welded together at 33 to form the complete construction.

Annular reinforcing portions are provided for 5 the chimes 34 of the barrel, the ring portion 35 being made from a bar of greater width than thickness and is formed into ring shape on the greater dimension to provide width to the chime end. The metal is pressed about the ring at the 10 end of the chimes, as illustrated in the Fig. 1. Preferably, before the rolling operation the name of the manufacturer or other indicia 36 is formed on the end surface of the chime for the purpose of roughening the surface to prevent the slippage 15 of the barrels when one is stacked upon another.

A suitable insulating material 37 may be provided between the inner container portions 10 and the outer reinforcing portions 18 of the barrel before assembly, as illustrated in Fig. 1, to 20 increase the insulating qualities of the barrel against the transfer of heat.

The employment of the insulating material 32, which is preferably non-compressible, between the 25 surfaces 11 and 22 of the inner and outer container portions 10 and 18, provides a support for the inner container portion against both lateral and longitudinal shifting so that the inner container portion is entirely insulated at the supporting portion which rigidly retains the inner 30 portion against movement relative thereto.

The flanges 24 and 26 of the inner container portions 10 and the outer container portions 18 are adjacent to the collar 13 and are welded together to form a unit construction. This prevents 35 a leak, which may occur between the collar and the inner container portions 10, from passing liquid between the inner container portions 10 and the outer reinforcing portions 18 of the barrel.

40 Before the tap bung 16 is screwed into the collar 13 a name plate 38 may be disposed over the head 19 of the barrel. The name plate is provided with an opening in the center over which the shoulders of the bung 16 extend and force 45 the name plate into firm fixed relation to the head 19 of the barrel. The edges of the name plate 38 may be spot welded or otherwise secured at the outer edges to the head 19 of the barrel. A government stamp retainer plate 39 may be 50 flanged over the tap-bung 16.

55 As a further extension of my invention I have illustrated in Fig. 3 the reinforcing band 27 as being divided into portions 40 and 41. The portion 40 is similar to portion 41 with the exception that an extending flange 42 is provided having an inturned end portion 43 which acts as a guide for the end 44 of the outer reinforcing portions 18 of the barrel. The end portion 43 guides and positions the ends 44 relative to each other 60 so that they will be in aligned relation when welded. In this manner the two reinforcing portions 40 and 41 are welded to the bilge portions or end portions of the reinforcing portions 18 of the barrel and one portion press fitted over the 65 extending end 43 to have its end guided into abutted relation and retained therein during the welding operation.

70 The barrel thus constructed is entirely insulated except for the metal bungs which contact the liquid within the barrel and is completely reinforced at the bilge and chime portions to provide strength and to prevent distortion and damage. The inner container portion is supported by the outer container portion through congruent sur-

faces which engage an insulating material in such manner as to provide both lateral and longitudinal support to the inner container portion. The chime ends are made wide to provide stacking surfaces which may be roughened by embossing indicia to insure against slippage when stacked. 5

While I have described and illustrated but a single embodiment of my invention, it will be apparent to those skilled in the art that various changes, omissions, additions and substitutions 10 may be made therein without departing from the spirit and scope of my invention as set forth in the accompanying claims.

I claim as my invention:

1. A barrel having an inner container portion 15 provided with reversely curved shoulder portions and an outer reinforcing portion having pressed-in chime portions providing surfaces which are congruent to the surface on the inner container portion, and an insulating material rigidly maintained between said two surfaces for supporting said inner element against lateral and longitudinal movement. 20

2. An all-metal barrel having an inner metal liquid container portion provided with reversely 25 bent shoulders, an outer reinforcing portion having a pressed-in head and chime portions forming surfaces congruent to said shoulders and insulating material compressed between said portions when said barrel is secured together to insulate said portions and to provide support 30 against relative lateral and longitudinal movements.

3. A barrel having an inner container portion with the ends reversely bent in S-shape to provide shoulders, a reinforcing portion spaced from said container portion having pressed-in head and chime portions forming surfaces congruent to said shoulders, and insulating material between 35 said surfaces and shoulders upon which they are clamped when the outer reinforcing portions are secured together to insulate the end portions and to support the portions against lateral and longitudinal movement. 40

4. A barrel of the all-metal type having a central liquid container portion provided with a pressed-out head at the ends forming shoulders, pressed metal pot-shaped reinforcing elements forming the outer surface of the barrel the head ends of which are outwardly extended forming shoulders which are congruent to said first shoulders and insulating material disposed between said shoulders and pressed thereby to provide lateral and longitudinal support to the inner container portion. 45 50

5. A barrel of the all-metal type having an inner liquid container portion the ends of which are extending forming reversely curved surfaces; like outer reinforcing portions extending over said inner portion having the head ends outwardly extended to provide shoulders of reversely curved surfaces which are congruent with said first surfaces, an insulating material provided between said shoulders which press thereon for supporting the inner container against lateral and longitudinal movement. 55 60

6. A barrel of the all-metal type having chimes formed on the end thereof, a reinforcing ring having a greater width than thickness secured to the ends of said chime to provide width to the barrel ends, and indicia provided on the chime ends and projecting thereabove. 70

BERTIL T. LINDELL.
